FIG. 3.

INVENTOR

ARTHUR F. LEVITT.

BY *Hazard E. Miller*

UNITED STATES PATENT OFFICE.

ARTHUR F. LEVITT, OF SOUTH PASADENA, CALIFORNIA.

COMBINATION STAMP, CRUSHING, AND GRINDING MILL.

1,247,293.

Specification of Letters Patent. Patented Nov. 20, 1917.

Application filed March 8, 1917. Serial No. 153,323.

To all whom it may concern:

Be it known that I, ARTHUR F. LEVITT, a citizen of the United States, residing at South Pasadena, in the county of Los Angeles and State of California, have invented new and useful Improvements in Combination Stamp, Crushing, and Grinding Mills, of which the following is a specification:

This invention relates to an ore mill and particularly pertains to a combined crushing and grinding mill for use in the amalgamation process of ore recovery.

It is an object of this invention to provide a mill for the treatment of ores and the recovery of precious metals which has a combined action to stamp or crush the ore and thereafter grind it by a continuous operation and use of one set of operating elements.

Another object of this invention is to provide a mill for the treatment of ores and the recovery of precious metals therefrom which will subject the ore to a simultaneous crushing and grinding blow, thereby causing the ore to be forcefully struck and ground during a single movement, thus insuring that the ore will be quickly separated from the metal without becoming lost and without the amalgam being floured, as is common in stamp mills and the like, where the ore is given a direct and powerful stamping stroke.

Another object of this invention is to provide an ore treating machine which will cause the ore to continuously move over the grinding floor and will permit it to fall at certain intervals in a manner to disintegrate it and permit it to come in contact with the amalgam without being struck by the grinding element.

Another object of this invention is to provide an ore mill which will positively and automatically clear itself of the tailings and insure that the screens through which the tailings flow will be maintained in a desirable and cleaned condition.

Another object of this invention is to provide a grinding mill designed along the lines of an arrastre which is fitted with a floor of peculiar construction so that pockets of amalgam may be distributed over its grinding surface in a manner to entrap the metals freed from the ore and cause them to be recovered without difficulty.

Another object of this invention is to provide means for retaining the large particles of ore within the mill until they have been

thoroughly pulverized and at the same time permitting the tailings to be drawn from the mill in a continuous manner without carrying away the amalgam.

Another object of this invention is to provide grinding and crushing elements which may be easily replaced and which are drawn by a mechanism of simple construction.

Another object is to provide feed means for the mill which will permit raw material to be continuously fed to the grinding floor without interruption of the operation of the driving mechanism.

Another object of this invention is to provide means whereby the grinding floor may be easily uncovered and the amalgam cleaned therefrom.

It is a further object to provide a mill of the above class which may be constructed of stone, metal, or other materials and which will operate equally well regardless of the material from which it is constructed, thereby providing a mill which may be easily set up in remote localities and inexpensively operated.

Other objects will appear hereinafter.

The invention is illustrated, by way of example, in the accompanying drawings in which:

Figure 1 is a view in side elevation illustrating the mill as assembled for operation and with parts broken away to disclose the detail formation of the grinding floor.

Fig. 2 is a view in plan elevation and section as seen taken on a line directly below the driving head and as disclosing the distribution of grinding members around the floor and the manner in which water is supplied to said floor.

Fig. 3 is an enlarged fragmentary detail elevation showing how a grinder jumps an amalgamating pocket.

Referring more particularly to the drawings, 10 indicates a base, which is here shown as circular in formation and supported upon supporting posts 11. This base may be formed of any desired material but is preferably formed of concrete and is adapted to provide a support for a grinding floor 12. 105 The grinding floor is also circular in plan and is formed with a series of radial serrations 14 upon its face. These serrations extend upwardly from the floor and are arranged circumferentially therearound. As 110 here shown, the inclined face 15 of each serration is disposed at substantially twenty-

two and one-half degrees to the vertical, and the wall 16 is preferably formed at right angles to this face. Various materials treated and the speed of operation will determine this angle, however. It will thus be seen that a V-shaped pocket 14' is formed for the reception of amalgam to be utilized in the recovery of the ore. Surrounding the grinding floor is a wire inclosure 17 which 10 prevents large pieces of ore from passing out with the tailings into a sluice-way 18. The inclosure is bounded along its lower edge by a continuous baffle strip 19 which partially closes the outer ends of the serrations and forms a trap for the amalgam and fine stuff settling therein.

A center shaft 20 extends vertically through the base and provides a mounting for a driving head 21. This head is disposed in a horizontal plane and is fitted with a series of drag chains 22 which depend from its under face and are connected to grinding members 23. These members, as particularly shown in Fig. 1 of the drawings, have a flat face adapted to bear upon the inclined face 15 of each serration as the driving head rotates in the direction of the arrow —a—. The rear face of the grinding members is here shown as disposed at an angle of less than ninety degrees to the grinding face, although this angle may be varied and thereby will provide clearance 16' between it and the vertically inclined face 16 of the serrations. This allows the 30 grinding elements, which are of considerable weight, to fall from the apex of the tooth to the gullet with considerable force. This will crush the ore and as the grinding element is dragged along the face 15 of the 35 serration the ore thus crushed will be ground. The driving head may be rotated by any desired source of power and is here shown as formed with a rim gear 24 in mesh with a pinion 25 by which it is driven. 40 This pinion is mounted upon a drive shaft 26 to which power is transmitted by a belt 27.

In order to permit the mill to be continuously fed, a hopper 28 is positioned above 50 the driving head and provided with a radially extending chute 29. This chute extends outwardly over the edge of the driving head and is formed with a downwardly turned elbow 30. An inturned trough 31 is secured 55 at the bottom of the chute and acts to direct the ore from the hopper in between the driving head and the grinding floor. It will be noted that due to the manner in which the grinding elements are connected to the head, 60 the ore will fall around and over these elements and will finally settle within the pockets of the grinding floor as the operation of the machine continues and thereby insure that the reduced ore will be thoroughly subjected to the action of an amalg-

mating agent. The driving structure is reinforced by means of side posts 32 and 33 which extend vertically at opposite sides of the mill and provide support for stay rods 34 and 35 connecting with a collar 36. This 70 collar is positioned around the upper end of the center shaft 20 and acts to give it stability.

In operation, ore or other material to be treated is placed within the hopper 28 and fed down through the chute 29 to the grinding floor. Simultaneous with which action the driving head 21 is rotated in the direction of the arrow —a— and the driving elements 23 and thus drawn over the grinding 80 floor. As these elements move along their course of travel they will successively ride up along the inclined faces 15 of the serrations and thereafter will fall with considerable force upon the face of the succeeding 85 serration. The angle of the face 16 and the speed at which the grinding elements move will determine the approximate point at which the element will strike the face of each serration after having fallen from the crest of the preceding one. In any case, the 90 operation of the machine is such as to insure that the grinding element will not fall directly into the gullet of the serration, as this lowermost crevice is reserved as a pocket 95 for the amalgam and pulp which is drawn over the crest of the serration and permitted to amalgamate therein. Due to the fact 100 that the grinding element will not strike this body of pulp, the amalgam will be prevented from flouring and the pulp in combination therewith will be agitated to be thoroughly subjected to the amalgamating effect of the agent. As the grinding element strikes the 105 inclined face of each serration it will deliver a blow at an incline to the face and thereby produce a combined crushing and grinding action. The force of this obliquely delivered blow will cause the pulp and fine 110 stuff to splash outwardly through the screen 19 and into the sluice-way 18, thus automatically clearing the grinding floor of useless material. As the elements ride up over the inclined faces they will continue to grind the pulp and reduce it. This material will 115 be raked over the crest of the serrations and permitted to fall free into the amalgam pockets. At the same time, water is being delivered from the sprinkler pipe 37 and will permit desirable results to be more efficiently obtained. When the mill has been 120 operated a sufficient period of time, the driving head 21 may be raised upon the shaft 20 and the grinding elements removed from the floor. The amalgam may then be drawn 125 off from the grinding floor and the recovery of the metals completed. Especial attention is called to the V-shaped amalgamating pockets 14' produced by the angular arrangement of the front moderately inclined 130

- faces 15 of the serrations 14, and the nearly vertical rear face 16, together with the inclined rear faces of the grinding members 23, which produces the clearance 16' between 5 a grinding member and a serration as the grinding member passes from one serration to the next, thereby causing the grinding member to jump the amalgam in the pocket 14'.
- 10 It will thus be seen that the mill here disclosed is simple in its construction and at the same time produces a combined crushing and grinding action by the continuous operation of its grinding members.
- 15 While I have shown the preferred construction of my ore mill as now known to me, it will be understood that various changes in the combination, construction, and arrangement of parts may be made by 20 those skilled in the art without departing from the spirit of my invention.
- I claim:
1. In an ore mill, a circular grinding floor having radial serrations extending upwardly, the front side of each serration being at a moderate incline and the rear side of each serration being substantially at right angles to the front side, thereby forming V-shaped amalgamating pockets, amalgam in the amalgamating pockets, a grinding member having a flat lower face adapted to bear upon the front inclined faces of the serrations, said member having a rounded corner formed by its lower and rear faces to 30 prevent the grinding member from seating within the amalgamating pockets formed by the meeting of the adjacent serrations, a rotating member above the grinding floor, and a connection between the grinding member 35
- and the rotating member; so that the grinding member is dragged from serration to serration; the angles, arrangement, and speed being such that the grinding member will jump the pocket of amalgam as it passes from one serration to the next. 40
2. In an ore mill, a circular grinding floor having radial serrations extending upwardly; the front face of each serration being disposed at a moderate incline to the horizontal and the rear face of each serration being substantially at right angles to the front face, thereby forming V-shaped amalgam pockets; the faces of which are exposed at angles to the vertical and horizontal; amalgam in said pockets, a freely moving grinding member having a flat lower face adapted to bear upon the front inclined face of the serrations and a flat rear face disposed substantially at right angles to the lower face and formed with a curved 45 lower edge to prevent the grinding member from seating within the gullet of the amalgam pocket, a rotating member above the grinding floor, and a flexible connection between the grinding member and the rotating member whereby the grinding member may be dragged over the grinding floor and from serration to serration; the angles of the serrations and the rounded rear corner of the grinding member serving to cause the 50 grinding member to jump from the front face of one serration to the front face of the other without seating within the gullets of the serrations. 55
5. In testimony whereof I have signed my name to this specification. 60

ARTHUR F. LEVITT.
